ATTORNEY

UNITED STATES PATENT OFFICE

CHARLES L. SHANK, OF NORTH CANTON, OHIO, ASSIGNOR TO THE HOOVER COMPANY,
A CORPORATION OF OHIO

SUCTION CLEANER AGITATOR

Application filed January 2, 1929. Serial No. 329,871.

This invention relates to suction cleaner rotors or agitators of the rotary type which are adapted to be mounted in the suction cleaner nozzle.

5 Heretofore agitators have necessarily been of a large diameter because of the impossibility in die casting of removing the small core from an agitator of small diameter. The use of a large diameter agitator necessitates a large nozzle and a consequent large nozzle opening into which the carpet or article being cleaned, when the machine is in operation, is drawn. The area of floor covering drawn into the nozzle varies directly 10 with the nozzle width and the resistance of movement of the suction cleaner over the floor is greatly increased, even to a degree where it is burdensome, through the unnecessary displacement of too great an area of 15 such covering. It is clear that with a small diameter agitator the nozzle dimensions could be decreased with the resulting desirable drop in resistance to movement of the machine.

20 As the cleaning action in a suction cleaner takes place over a limited area only of the nozzle opening and as a decrease in the size thereof would have no detrimental effect upon the cleaner efficiency the desirability of a 25 relatively small nozzle is apparent and the value of a small agitator which is still commercially feasible is obvious.

The object of my invention is, therefore, the provision of a suction cleaner agitator 30 combining all the desirable features of a relatively large agitator yet which is itself of small diameter.

A further object of my invention is to provide a small diameter agitator for suction 35 cleaners which is so designed and constructed that its small diameter does not prevent its manufacture by ordinary manufacturing methods such as die casting.

40 Other objects and advantages will be apparent as the description proceeds.

In the drawings accompanying and forming a part of this application wherein is illustrated a preferred embodiment of my invention:

50 Figure 1 represents a longitudinal cross

section through my invention disclosing the parts in assembled relation.

Figure 2 is a transverse cross section at the line A—A of Figure 1.

Figure 3 is a transverse cross section at the line B—B of Figure 1.

In the drawings like parts are indicated by the same reference characters throughout.

In accordance with my invention the agitator is composed of a plurality of individual 60 interfitting members forming, in their assembled relation, a symmetrical whole. Referring to Figure 1 reference characters 2 and 3 indicate the two interfitting semi-cylindrical members forming the body of the agitator indicated generally by 1. Part 2 constitutes a female member being provided at its ends with portions 4 and 5 between which the member 3 is positioned. A brush seat 7 in each member is provided by reentrant walls 70 therein and is adapted to, seat and retain a brush 8. The brush is easily mounted in the seat 7 as the ends of the brush back are reduced in thickness and are adapted to be inserted a sufficient distance into either end of 75 the seat, said seat being greater in length than the brush back, to permit the opposite end of the brush back to be inserted into the opposite end of the seat after which the brush may be centered. The brush seats 7, 7 are 80 located on diametrically opposite sides of the agitator and also on the opposite sides of the longitudinal center. Securing means 6 pass through each of the members 2 and 3 along the greatest diameter and are secured to the bottom face 11 of the brush seat 7 in the opposing member and have their heads countersunk to eliminate irregular projections upon the agitator surface. Beater elements 9—9 are 85 attached to the surface of the members 2 and 3 as in the usual agitator. Bearings 10—10 are shown secured in the members 4 and 5 which carry the agitator when in position in a cleaner. The surfaces of both members 2 and 3 are formed with an uninterrupted portion at substantially their respective centers which coact, when the agitator is assembled, to form suitable belt-receiving means in order 90 that the agitator may receive a rotating force.

It is seen from the foregoing description 100

- that I have provided an agitator comprising all the desirable features of the present day agitator and which, because of its novel design, includes no hollow members from which 5 a core must be drawn longitudinally in die casting and therefore permits of construction in relatively small sizes commercially.
- I claim:
1. An agitator for suction cleaners comprising a body formed of a plurality of complementary members, one of said complementary members extending the length of said body and formed with integral ends, agitating elements carried by said body, and supporting means mounted solely on the integral ends of said one complementary member. 10
  2. An agitator for suction cleaners having a body-portion, complementary members forming said body-portion, reentrant portions in said complementary members forming brush seats, securing means holding said complementary members in assembled relation comprising rivets extending diametrically in said body being secured at one end to 15 a reentrant portion of a complementary member, and brushes mounted in said brush seats. 20
  3. In an agitator for suction cleaners a female body-member formed of a semi-cylindrical shell between its ends, cylindrical portions forming the ends of said female member, a male body-member formed of a curved hollow shell positioned between said cylindrical portions of the female member and complementing said female member in the 25 formation of a cylindrical body portion and supporting means in the longitudinal axis of said body portion carried by said female member. 30
  4. In an agitator for suction cleaners a female body-member formed of a semi-cylindrical shell between its ends, cylindrical portions forming the ends of said female member, a male body-member formed of a semi-cylindrical shell positioned between said cylindrical portions of the female member and complementing said female member in the 35 formation of a cylindrical body, reentrant portions formed in said male and female members constituting brush seats, brushes positioned in said seats and agitating elements mounted on said body-members. 40
  5. An agitator for suction cleaners comprising a rotatable body, members complementing each other in the formation of said body, solid sections on one of said members forming the ends for said body and supporting means carried by said ends. 50
  6. In an agitator for suction cleaners, a plurality of complementary body-members, uninterrupted surface portions at substantially the longitudinal centers of said body-members forming a belt-receiving pulley, longitudinally extending reentrant portions in said body-members forming brush seats upon 55 opposite sides of said pulley, said reentrant 60
- portions extending to the longitudinal axis of said agitator and supports for said agitator carried by one of said body-members at the ends thereof in the longitudinal axis. 70
- Signed at North Canton, in the county of Stark, and State of Ohio, this 21st day of December, 1928.
